UNITED STATES PATENT OFFICE.

ARTHUR H. GUSTAFSON, OF CHICAGO, ILLINOIS, ASSIGNOR TO HENRY E. HOLBROOK,
OF BOSTON, MASSACHUSETTS.

MACHINE FOR SEALING CIRCULARS.

Application filed January 26, 1918. Serial No. 213,967.

To all whom it may concern:

Be it known that I, ARTHUR H. GUSTAFSON, a citizen of the United States, residing at Chicago, in the county of Cook and State 5 of Illinois, have invented an Improvement in Machines for Sealing Circulars, of which the following is a specification.

This invention relates to means for applying sealing wafers to various kinds of 10 circulars or other publications. In the embodiment of the invention herein shown, mechanism is adapted to apply a gummed wafer across the contiguous edges of a folder to hold the latter in folded position 15 for mailing or the like.

It is an object of the invention to produce a machine of the character described which will be simple and economical in construction and efficient in operation.

20 In the drawings:—

Fig. 1 is a side elevation of the machine constructed according to my invention;

Fig. 2 is a plan view thereof;

Fig. 3 is an end elevation of the machine;

25 Fig. 4 is a cross sectional view along the line 4—4 of Fig. 3;

Fig. 5 is a perspective view of the hopper for the wafers;

30 Fig. 6 is a perspective view of the stripping needle;

Fig. 7 is a perspective view of the wafer belt and its supporting mechanism;

Fig. 8 is a perspective view showing the folder about to be supplied with a wafer;

35 Figs. 9, 10, and 11 are side elevations showing the steps in the operation of applying the wafer to the folder;

40 Fig. 12 is a perspective view of a folder equipped with a wafer according to my invention.

Fig. 13 is a modification showing mechanism for sealing a folder having the edges folded upon one of the faces of the folder.

45 Folders to be sealed are contained in an adjustable hopper 1, the details of which will be hereinafter more fully described, and are successively drawn from the open bottom of this hopper by a pair of endless belts 2 equipped with lugs 3 adapted to push a single folder out of the hopper and carry it forward with the belts. The endless belts 2 are spaced apart, as clearly indicated in Fig. 2, and between them, adjacent the delivery end of the machine described here-

in is provided the mechanism for applying 55 the sealing wafers.

This mechanism comprises a wafer hopper 5, shown in perspective in Fig. 5, having one end partly closed as indicated at 6. Wafers 7 are stacked in the wafer hopper 5 so that a portion of the under side of the bottom one is exposed through the opening above the closure 6. The wafer hopper 5 is arranged upon a steep incline, as shown in Fig. 4, in such a fashion that 65 the bottoms of the wafers will successively be pushed into contact, by the weight of the wafers above (assisted by a weight, if desired), with a feeding member as an endless belt 8 running on rolls 9 and 10. Adjacent 70 the roll 9 is the roll 11, which presses the wafer into full contact with the belt, while the belt is kept moist by the wick 12 in the tank 13.

The lower roll 10 is of small size, as 75 clearly seen in Fig. 4, and adjacent thereto and just at the point where the belt 8 makes a short turn about the roll, is the end 14 of the adjustably mounted stripping needle 15, whose end runs in a groove 15' in the 80 belt 8. This needle serves to strip the wafer off the belt, as may be clearly seen in Fig. 7, the wafer then passing downwardly until it rests substantially vertically in a slot 16 in the standard 17. The slot 16 is flared 85 on its delivery side, as indicated at 18, and the pressure rolls 19 and 20 are provided, the lower one of which continues the curve of the flared portion 18 of the slot 16. The 90 operation of the mechanism can be clearly gathered from Figs. 7 to 12.

I will now describe in detail the structural elements of the illustrated machine, including the construction of the hopper for the folders and the parts for mounting the 95 various operating mechanisms above described. The folder hopper 1, see Fig. 2, comprises a pair of upright members 20^a adjustably mounted upon the frame members 55 respectively of the machine as by 100 means of the thumb nuts 22. To the uprights 20^a are secured the end plates 24 provided with lugs 25, to which are pivoted on opposite sides of the machine the arms 26, these arms at their opposite ends being pivotally mounted on upper and lower bolts 27 carried in long sleeves 28. Pivoted to 105 the bolts 27 adjacent the arms 26 are the

arms 30, Figs. 1, 2, each of which is, at its other end, pivoted to the side plates 31 by means of the long bolts 32 carried in lugs 33 on the side plates. The bolts 27 are 5 screw threaded at their adjacent ends and engaged by the collars 34 provided with handles 35 by which the bolts 28 can be drawn toward each other to tighten the pivotal joint of the arms 26 and 30 to maintain any desired adjustment.

The construction is such that the end plates 24 can be adjusted to accommodate any length of folder desired within the limits of the adjustment, while the side plates 15 31 may thereafter be set to accommodate any width of folder desired, within the possible range of adjustment of the machine.

The endless belts 2, see Figs. 1, 2, travel on rolls 40 at the rear of the machine and on 20 rolls 41 at the front of the machine. The rolls 40 are mounted on the shaft 42 having bearings in the frame work of the machine and are adjustable on the shaft by means of the adjusting bolts 43. The rolls 41 at 25 the delivery end of the machine are aligned with the rolls 40, are carried on a shaft 45 and similarly adjustable thereon by the bolts 46. By this means, the belts may be made to travel under the hopper at the correct 30 and desired distance apart. The rolls 40 are driven by the sprocket 50 fast on the shaft 42 and operated by the chain 51 from a suitable motor 52 carried on the frame-work of the machine.

35 The framework of the machine, Fig. 1, comprises the four legs 53 having a platform 54 to carry the motor and side bars 55. Secured to the two side bars 55, are the brackets 60 whose upper portions extend inwardly and terminate in the side plates 61. In the side plates 61 are the bearings for the shafts of the rolls 9, 10, 11, 19, and 20 hereinabove described. The shafts 40 of the rolls 20 and 10 extend through bearings in the plate 61 at one side and through one end of one bracket 60 (see Fig. 3) and are equipped with pulleys 65 and 66, over which is trained the belt 67. By this construction, it will be apparent that when the 45 roll 20 is revolved, the roll 10 will also be revolved and therefore the belt 8 caused to travel as well as the roll 11 in contact therewith.

55 The wafer holding standard 17, Fig. 4, is mounted upon a cross bar 70, Fig. 3, extending across the side frames of the machine, while the stripper 14, Fig. 4, is adjustably mounted upon the shaft 75, which is secured to the plate 61, by being passed through an aperture therein and the stripper 60 is secured by the thumb screw 76 to the shaft 75.

In operation, it will be apparent that, power being communicated to the shaft 42 as described, to the endless belts 2, will

travel, taking folders from the hopper and passing them through the sealing mechanism. Each time a folder goes between the rolls 19 and 20, it will revolve, in turn, the roll 20, which will revolve the roll 10 by 70 means of the belt pulley 67 (see Figs. 1, 2) which will cause the belt 8 to travel a pre-determined distance, thus bringing a new wafer down over the stripper needle 14 and into the slot 16. The next folder as it passes 75 between the rolls 19 and 20, will strike the wafer thus held in vertical position about midway on its gummed side and push this wafer through the rolls 19 and 20, folding the edges of the wafer down on the opposite 80 faces of the folder and sealing the same.

In Fig. 13 is shown a modified form of stripper needle 70 having a shorter flat folder engaging section 71, an upwardly extended similar portion 72 which may be curved slightly more in a forward direction and a stripping end 73. With this form of needle no standard 17 is used. This form is used where the wafer is to be applied to the flat surface of the folder, as when the folder is folded as shown in Fig. 13. In such case the folder, as it is carried forward, strikes the flat section 71, forcing the upwardly extended or needle portion 72 forward and the wafer 7 against the roll 19, 90 which draws the wafer off the needle and puts it on the folder, the roll being driven by the forward edge of the folder which has already passed between rolls 19 and 20. The continued rotation of the roll 19 will bring 100 a new wafer down on the portion 72 of the needle through the connections between the various rolls above explained. By locating the section 71 in different positions, the wafer may be applied in a wide variety of 105 locations on the folder to suit various kinds of folds.

It will be obvious that it is immaterial what the shape of the wafers may be. It will also be readily recognized that by the word "wafer" I do not refer merely to wafers composed entirely of adhesive material, but I include in the term wafers of paper, cloth or the like, gummed upon at least one side, and they may be of any preferred form such as Red Cross, Christmas or other stamps, or labels of fanciful outline.

Having described one embodiment of my invention which obviously is not limited to the construction disclosed, in all details, I claim:

1. In apparatus of the class described, means including endless carriers for feeding a folder or the like, a wafer magazine, a moistened carrying member for picking a wafer from the hopper and carrying it to a folder, means for stripping the wafer from the carrying means and for placing the wafer across the path of the folder, and a 125

- wafer supporter for holding the wafer across the edge of the folder.
2. In apparatus of the class described, means for feeding a folder or the like, a wafer magazine, a moistened carrying member for picking a wafer from the magazine and carrying it toward a folder, a wafer stripping member for stripping the wafer from the carrying member, means for positioning the wafer loosely across the plane of travel of the folder or the like where it may be impinged by the edge of the folder, and oppositely acting members for folding the wafer across the edge of the folder as the latter continues its movement after impinging the wafer.
3. In apparatus of the class described conveyors for feeding a folder or the like edge-wise uniformly forward in the machine, a moistened member for engaging a wafer and feeding it forward toward the folder, a pocket for loosely positioning the wafer across the path of travel of the folder and in a plane substantially at right angles thereto, whereby the wafer will be impinged and picked up by the folder moving uniformly forward, and pressing members for thereafter pressing the wafer upon both sides of the folder.
4. In apparatus of the class described, in combination, a wafer magazine, a moistened carrying member for picking a wafer from the magazine and for carrying it to a folder, a wafer stripping needle for stripping the wafer from the carrying means, and means acting to fold the wafer across the edge of a folder, and oppositely positioned means acting thereafter to press the halves of the wafer upon opposite faces of the folder.
5. In apparatus of the class described, folder advancing members, a wafer hopper, moistened means acting to pick the wafer from the hopper and to transfer it from the hopper, a stripping member for stripping the wafer from the transferring means and positioning one face of the wafer to the folder, and pressing members for securing the wafer upon the folder.
6. In apparatus of the class described, means for moving folders or the like through the machine, a hopper for wafers to be attached to the folders, a moist carrier adapted to successively take wafers from the hopper, and pressing means adapted to cooperate with the travelling folder for applying the wafers thereto.
7. In apparatus of the class described, a reservoir for folders or the like, a belt for taking the folders successively from the reservoir, a hopper adapted to contain wafers, a second belt for taking the wafers from the hopper successively, the belts being arranged in such relation that the wafers are carried by the second belt from the hopper to the plane of the first belt.
8. In apparatus of the class described, a belt for moving folders or the like through the machine, means for bringing wafers successively into and isolating the same across the path of the folders carried by the belt, 70 said last named means being operated from the belt.
9. In apparatus of the class described, a belt for moving folders or the like through the machine, means for bringing wafers successively into the path of the folders carried by the belt, 75 said means comprising a belt adapted to transfer wafers from a wafer hopper, and driving means for said belt frictionally operated from the first belt.
10. In apparatus of the class described, a belt for moving folders or the like through the machine, means for bringing wafers successively into the path of the folders carried by the belt, 80 said means comprising a belt adapted to transfer wafers from a wafer hopper, and driving means for said belt frictionally operated by the folders carried by the first belt.
11. In apparatus of the class described, a pair of belts adapted to successively advance folders or the like through the machine, wafer supplying means between the belts and adapted to supply wafers to the folders on the belts between the latter by isolating 90 the wafer from the supplying means and placing it in the path of the folder.
12. In apparatus of the class described, a pair of belts adapted to successively advance folders or the like through the machine, 100 wafer supplying means between the belts and adapted to supply wafers to the folders on the belts between the latter, said wafer supplying means being operated by said belts.
13. In apparatus of the class described, a pair of belts adapted to successively advance folders or the like through the machine, wafer supplying means between the belts and adapted to supply wafers to the folders 110 on the belts between the latter, said wafer supplying means being operated frictionally by folders carried by said belts, and means operated also frictionally by the folder for applying the wafer thereto.
14. In apparatus of the class described, a belt for advancing folders or the like successively through the machine, a second belt adapted to bring wafers successively into the plane of the first belt, means for stripping the wafers from the second belt and placing them in correct cooperative relation with the folders on the first belt.
15. In apparatus of the class described, a belt for advancing folders or the like successively through the machine, a second belt adapted to bring wafers successively into the plane of the first belt, means for stripping the wafers from the second belt and placing them across the plane of travel of 120 130

the folders on the first belt, whereby the wafers are bent over the edge of the folders as the latter pass through the machine.

16. In apparatus of the class described, a belt for advancing folders or the like successively through the machine, a second belt adapted to cause wafers successively to intersect the plane of the first belt, means for stripping the wafers from the second belt 10 and placing them across the plane of travel of the folders on the first belt, whereby the wafers are bent over the edge of the folders as the latter pass through the machine, and rollers for pressing the halves of the wafers 15 upon the faces of the folder.

17. In apparatus of the class described, a belt for causing folders or the like to advance through the machine, a second belt for bringing wafers into the plane of the 20 first belt, means for stripping the wafers from the first belt and placing them in correct cooperative relation with the folders advanced by the first belt, and rollers for pressing the wafers upon the folders.

25 18. In apparatus of the class described, a belt for causing folders or the like to advance through the machine, a second belt for bringing wafers to the plane of the first belt, means for stripping the wafers from 30 the second belt and placing them in correct cooperative relation with the folders advanced by the first belt, and rollers for pressing the wafers upon the folders, said rollers being caused to operate by the folders on the 35 belt.

19. In apparatus of the class described, a belt for causing folders or the like to advance through the machine, a second belt for bringing wafers into the plane of the 40 first belt, means for stripping the wafers from the second belt and placing them in correct cooperative relation with the folders advanced by the first belt, and rollers for pressing the wafers upon the folders, said rollers being frictionally and intermittently driven during the passage therebetween of a folder on the first belt.

20. In apparatus of the class described, a 50 pair of belts for causing folders or the like to advance through the machine, said belts being spaced apart, wafer supplying means, comprising means for transferring wafers from a remote point to the plane of the belts, means for stripping said wafers from said transferring means, and means for causing said wafers to adhere firmly to the folders, said wafer supplying means being interposed between said belts.

55 21. In apparatus of the class described, a 60 pair of belts for causing folders or the like to advance through the machine, said belts being spaced apart, wafer supplying means, comprising means for transferring wafers from a remote point to the plane of the belts, means for stripping said wafers from

said transferring means, and means for causing said wafers to adhere firmly to the folders, said wafer supplying means being interposed between said belts, and operated frictionally by the folders upon said belts. 70

22. In apparatus of the class described, a pair of belts for causing folders or the like to advance through the machine, the belts being spaced apart, wafer supplying means, comprising means for transferring wafers 75 from a remote point to the plane of the belts, means for stripping said wafers from said transferring means, and means for presenting the wafers to the folders, the wafer supplying means being interposed between 80 the belts and operated frictionally by the folders upon said belts.

23. In apparatus of the class described, means for moving folders or the like through the machine, a hopper for wafers, a moist member for picking the wafers from the hopper and transferring them successively therefrom, means to strip the wafers from the transferring means, and means to receive the wafers as they are stripped and position them to be received by the folders. 85

24. Apparatus of the class described comprising a label transferring member, a label magazine presenting labels successively thereto, a folder or the like conveyor causing the folder to intersect the path of the label and feed the label between label applying members, and label applying members acting to cause the label transferring member to successively present labels for action 95 by the applying members. 100

25. Apparatus of the class described comprising a label hopper, a moistened label transferring member adapted to pick a label from the hopper and present it in a position to be engaged by a folder, a folder conveyor travelling adjacent the label transferring member and adapted to present the folder across the plane of the moving label while the transferring member for the label and the folder conveyor are both in motion. 110

26. Apparatus of the class described comprising a moistened label picking and transferring member, a folder conveyor acting to present the folder edgewise to the label, and a pocket to receive the label from the transferring member pending its application to the folder. 115

27. In apparatus of the class described, a flexible conveyor for feeding folders or the like, a moistened stamp carrying member for selecting a stamp and carrying it toward the folder, a pointed stripper member for stripping the stamp from its carrying member and guiding it endwise to cause it to intercept the folder, and means for securing the stamp upon the folder. 120

28. In apparatus of the class described, a conveyor for feeding the sheet to be wafered or stamped, a rotatable moistened member 125 130

for selecting and feeding the stamp, a thin edged stripper for stripping the stamp from its conveyor, a holder to retain the stamp in and partly below the path of the sheet, and 5 means for securing the stamp to the sheet.

29. In apparatus of the class described, means for feeding a folder or the like, a wafer magazine, rotatable means for carrying a wafer to the path of the folder, means 10 for stripping a wafer from the carrying means, a pocket for supporting the wafer in the path of the folder, a moist selecting member for simultaneously selecting from the magazine and moistening the wafer, and 15 wafer pressing and smoothing members for

applying the wafer to the folder and smoothing the same upon the surface thereof.

30. In apparatus of the class described, a frame 55, a wafer supporting standard 17, a folder feeding member 2, a wafer magazine 6, a wafer transferring member 8 travelling adjacent said magazine, means for moistening the wafer, the wafer stripping member 15 for moving the wafer from the transferring member, the wafer applying 20 rolls 19, 20, for applying and smoothing the wafer upon the surface of the folder. 25

In testimony whereof, I have signed my name to this specification.

ARTHUR H. GUSTAFSON.
